MARKING GAUGE

Harold R. Rippon, East Lynn, Mass., assignor to
The Stanley Works, New Britain, Conn., a cor-
poration of Connecticut

Application October 29, 1949, Serial No. 5,770

Term of patent 14 years

(Cl. D52—1)

To all whom it may concern:

Be it known that I, Harold R. Rippon, a citizen of the United States, residing at East Lynn, in the county of Essex, State of Massachusetts, have invented a new, original, and ornamental Design for a Marking Gauge, of which the following is a specification, reference being had to the accompanying drawing, forming a part hereof.

In the accompanying drawing:

Figure 1 is a side view of a marking gauge embodying my new design.

Figure 2 is a top plan view of the marking gauge shown in Fig. 1.

Figure 3 is an end view of the marking gauge shown in Figs. 1 and 2 as viewed from the left-hand end of said figures.

I claim:

The ornamental design for a marking gauge, substantially as shown.

HAROLD R. RIPPON.
